SR

OR D 15,812

Dec. No. 15, 812

UNITED STATES PATENT OFFICE.

FRANK BENJAMIN, OF LANSINGBURG, NEW YORK.

DESIGN FOR A NEEDLE-WORK HOLDER.

SPECIFICATION forming part of Design No. 15,812, dated February 17, 1885.

Application filed December 3, 1884. Term of patent 14 years.

To all whom it may concern:

Be it known that I, FRANK BENJAMIN, of the village of Lansingburg, county of Rensselaer, State of New York, have invented and 5 produced a new Design for a Needle-Work Holder, of which the following is a specification.

My design relates to the ornamental and useful form of a needle-work holder; and, as 10 shown in the annexed photograph, forming a part of this specification, my design consists in the dish-form receptacle D, having scalloped outer edges, a, the pedestal P, having the scroll-form feet F, the vertical standard S, 15 which is projected through and so as to extend above the said dish-form receptacle, said standard having near its base the radially-arranged and upwardly-projected thimble-arms T, and at its top the needle-cushion cup C, and 20 between the latter and the said thimble-arms the two sets of spool-arms A' A'', all of which spool-arms are curved upwardly and out-

wardly and each made with the spool-buttons b near their outer ends.

Having thus described my design, what I 25 claim, and desire to secure by Letters Patent, is—

The design for a needle-work holder, consisting of the pedestal P, having feet F, the standard S, the dish-form receptacle D at the 30 base of the standard, the thimble-holders T, fixed to the standard above the dish-form receptacle, the two sets of upward-curved rods A' A'', terminating in spool-holders b, and the cup-form needle-cushion C on the top of the 35 standard, all as shown and described.

Signed at Troy, New York, this 7th day of November, 1884, and in the presence of the two witnesses whose names are hereto written.

FRANK BENJAMIN.

Witnesses:

STANLEY M. HOLDEN,
GEO. M. PAYFER.
